B. F. ORDWAY

AUTOMATIC CUT-OFF PLUG FOR ELECTRIC IRONS

Filed Sept. 9, 1925

UNITED STATES PATENT OFFICE.

BENJAMIN FRANKLIN ORDWAY, OF PASADENA, CALIFORNIA.

AUTOMATIC CUT-OFF PLUG FOR ELECTRIC IRONS.

Application filed September 9, 1925. Serial No. 55,382.

The object of this invention is to provide a cheap, simple, and effective means for cutting off the electric current from electric irons to prevent the same from becoming 5 excessively over-heated.

It is a common occurrence for the user of an electric smoothing iron to leave the same on the ironing board while the iron is connected to the electric service and such irons 10 are likely to be neglected and to become so over-heated as to burn garments, ironing cloths and ironing boards upon which the electrically connected iron is left, and in many instances, destruction by fire, of the 15 building in which the iron became over-heated, has resulted.

An object of this invention is to provide a cheap, simple and effective means for preventing such occurrences, and this I do by 20 providing an electric plug having contacts adapted for connection with the terminals of a heating circuit and connections for terminals of a source of electrical supply; a stationary switch contact adapted to be connected to one of such terminals; a movable switch contact adapted to be connected to the other terminal; a manually operated switch key to electrically connect and disconnect the switch contacts; a spring tending 25 to normally hold the movable switch contact out of contacting position; means adapted to hold the movable switch contact in contacting position; and a fuse adapted to be held in thermal contact with 30 the smoothing iron, and also adapted to hold the movable contact holding means in spring compressing position while the fuse is in place; said fuse being adapted to be melted and to release the movable contact 35 when the iron becomes over-heated.

In this connection I have provided an insulating plug having a way therein, and have provided in said way, a slide having shoulders at its ends, one of said shoulders 45 being adapted to be spaced from the end of the insulating member to hold a spring-pressed contact member in contacting position while the fusible plug is unfused.

An object of the invention is ready 50 storing of the plug to operative condition, after a fuse has been melted; and in this connection I provide a tape formed of fusible material and blocked off by creases to form a united series of fuses of a size 55 adapted to be used in the plug, so that when

a fuse has been melted, a new fuse may be broken off of the tape and inserted in place.

An advantage of using a tape formed of fusible material is that the same may be wound around or otherwise secured to the 60 electric cord so that it will always be readily available.

An advantage of this invention is that a fuse may be immediately inserted in place by simply detaching the plug from the iron, 65 and the iron may be left free to be used until re-heating is required, whereupon the plug may be restored.

Other objects, advantages and features of invention may appear from the accompanying drawing, the subjoined detailed description and the appended claims.

The invention may be applied in various forms with either a revolvable or a sliding key. An illustration of the sliding key 75 form will be sufficient for a clear understanding of the invention.

The accompanying drawing illustrates the invention with the slide key.

Figure 1 is a perspective view of a plug so constructed in accordance with this invention and having a slide key. The plug is shown connected to a smoothing iron.

Fig. 2 is a side elevation of the plug shown in Fig. 1 attached to the iron; the key is 85 shown in connecting position and a part of the skirt is broken to expose the fuse retained disconnecting bar.

Fig. 3 is a view of the plug as shown in Fig. 2 the insulating cap shown in Fig. 2 90 being removed to one side to expose the interior parts.

Fig. 4 is a fragmental view of the plug as shown in Fig. 3, with a fragment of the cap in place and showing the position of 95 parts after the fuse has been melted.

Fig. 5 is a view of the attaching end of the plug with fuse in place.

Fig. 6 is a section on line α^6 , Figs. 2, 3, 4 and 5 with fuse in place.

Fig. 7 is a view in section on line α^7 , Figs. 2, 3, 4 and 5, with fuse in place.

Fig. 8 is a fragmental edge view of a strip of fuses.

Fig. 9 is a face view of the strip of fuses. 105

The electric plug is shown as comprising an insulating shell formed of two members 1, 2, in which are mounted contacts 3, 4, adapted to clamp upon the terminals 5, 6 of the heating circuit, not shown, of the iron 110

7 to be heated by such heating circuit in a well known manner.

8 and 9 indicate the leads from the source of electric supply. The lead 8 is connected by the binding post 10 with the contact 3, and the lead 9 is connected by binding post 11 with a movable switch contact 12, that is normally held in contacting position by means of a fuse 13, formed as a block.

10 14 indicates means in the form of a shoulder on a slide 15, sliding in a way 16, and having a standard 17 that has an overhang 18, to which an arm 19 is fixed by a rivet 20.

15 A spring 21 is arranged to normally tend to retract the slide 15 when the fuse 13 is not in place between the shoulder 14 and the end of the shell, the member 1 of which is cut away at 22 to form a seat that will prevent the fuse from being moved when the 20 shoulder 14 is held compressed against the same by the tension of the spring 21.

16 The lead 9 is connected to the arm 19 and the movable switch contact point 12 by means of the binding post 11, and when the 25 fuse 13 is in place the contact point 12 is held in the position indicated in Fig. 3, spaced apart from the spring 24.

25 is a switch key fixed to and operating the conducting member 26 of the key switch. 30 One end of said conducting member as at 27 is adapted to always be in contact with the contact spring 24 and when the fuse is in place and the key is drawn out as indicated in Fig. 4, the conducting member 26 of the switch will wedge against the movable switch contact 12, and sliding thereupon will give a good electrical connection from the movable switch contact 12 through the conductor 26, spring 24, and the contact 40 to the terminal 6, thence through the heating circuit, not shown, and the terminal 5 to the lead 8.

45 When the iron 7 becomes over-heated, that is, heated beyond the temperature required for ironing or other normal use of the heated iron, the heat from such iron will melt the fuse 13, thus allowing the spring 21 to retract the shoulder 14 from thermal connection with the iron and will move the movable contact point 12 out of contacting position, so that the electrical circuit is broken irrespective of the connecting position of the key.

55 The slide 15 is provided with a thumb piece 28 struck up from the slide and adapted to serve as a handle for sliding the slide into the extended position shown in Figs. 2, 3, 6 and 7, so that another fuse may be inserted in place.

60 Said handle 28 is shown struck out to form a slot 29 through which the screw 30 that holds the two halves 1 and 2 of the insulating shell together, extends;

Said screw being screwed into the nut 31. 65 Said screw and nut also serve to hold the

hood 32 in position; bolts 33, 34 being also employed in the usual manner to hold the members 1 and 2 together.

In the form shown, the member 1 of the insulating shell is recessed at 35 to receive 70 the end of the bolt 36 that holds the spring clips of the contact 4 in place. This recess also forms a seat for said bolt 35 to hold the contact 4 in place.

The point 27 of the conductor is adapted 75 and arranged to be held in contact with the spring 24, and the point 27' of said conductor is constructed and arranged to be out of contacting position relative to the movable contact 12 when the key is in position to 80 break the circuit.

This arrangement prevents accidental displacement of the key to produce a contact 85 with the movable switch contact when the fuse is in place.

The fuse ribbons 13' are shown separated 90 into fuses 13 by creases 37 and the fuse may be made of a composition of lead, tin and bismuth in such proportions as will cause the fuse to become melted at the required temperature.

The strip of fuse may be readily attached 95 to the electric cord and will not interfere with the use of the same, and will thus always be at hand when needed.

I claim:

1. The combination with an electric plug for connecting the heating circuit of an electric iron with a source of electrical supply; of a movable switch contact; means to move such switch contact out of contacting position; and a fuse held in position to be heated by the iron, and adapted to maintain the movable switch contact in contacting position, and to be melted by over-heat of the iron; said contact moving means being adapted to move the movable contact from contacting position when the fuse is melted, and manually operated means to connect and disconnect the circuit through the movable contact. 105

2. The combination with an electric plug for heating irons; of a switch and a spring-operated slide provided with a shoulder; and a fusible block adapted to be inserted 110 between the shoulder and the plug body and to be brought into position to be fused by the iron when the iron is over-heated by the electric current and said spring for said slide being arranged to move the slide to open the switch when the block is fused.

3. The combination with an electrical plug having a contact and a spring electrically connected therewith; of a switch conductor adapted to be moved into and out of conducting position; a movable switch contact adapted to be moved into and out of contacting position; a slide adapted to hold a fuse in position to be melted by over-heat 125 ing by a body heated by electrical current 130

through the contact; and means to move the slide and adapted to move the movable switch contact out of contacting position when the fuse is melted.

- 5 4. The combination with an electrical plug having a movable switch contact and a conducting spring; of a key having a means adapted to connect the movable contact and the conducting spring, said means being
10 adapted to contact with said spring when

out of and when in conducting position and to contact with both the spring and the movable contact when the movable contact is in contacting position and the conductor is brought into conducting position.

15

In testimony whereof, I have hereunto set my hand at Los Angeles, California, this 31st day of August, 1925.

BENJAMIN FRANKLIN ORDWAY.
